Patented May 30, 1916.

UNITED STATES PATENT OFFICE.

WALTER S. RUTLEDGE AND JOHN H. DE WEESE, OF DAYTON, OHIO.

NECKTIE-HOLDER.

1,185,348.

Specification of Letters Patent.

Patented May 30, 1916.

Application filed March 1, 1915. Serial No. 11,336.

To all whom it may concern:

Be it known that we, WALTER S. RUTLEDGE and JOHN H. DE WEESE, citizens of the United States, residing at Dayton, in the county of Montgomery and State of Ohio, have invented certain new and useful Improvements in Necktie-Holders; and we do declare the following to be a full, clear, and exact description of the invention, such 10 as will enable others skilled in the art to which it appertains to make and use the same, reference being had to the accompanying drawings, and to the letters and figures of reference marked thereon, which form a 15 part of this specification.

Our invention relates to new and useful improvements in necktie holders, or means for holding a number of ties together or in one package in a show case.

20 In retail stores, much annoyance is experienced in keeping quantities of ties in neat packages or bunches in show cases.

It is, therefore, the object of our invention to provide a neat clamp or holder which 25 engages the neck portions of a number of ties doubled and laid one upon another in bunches. The holder consists of a metal band which, owing to its smallness, does not encumber or interfere with the handling or 30 display of the ties.

In the accompanying drawings, Figure 1 is a plan view showing our improved holder clamping together a package of ties; Fig. 2 is a view at a right angle to Fig. 1; Fig. 3 is a perspective view of the clamp or holder; Fig. 4 is a cross-sectional view of the holder or clamp; Fig. 5 is a detached view of the movable plate; and Fig. 6 is a detail sectional view showing the manner of uniting 40 the springs to the frame and movable plate.

The holder comprises a rectangular frame having a base 1, sides 2—2, and top 3. This frame is essentially light and may be made of a variety of materials, such as thin sheet 45 metal, celluloid, gutta percha, and the like. Each of the side members has shoulders 4 formed thereon and the ends of two springs 5 are attached to the base 1. This attachment is conveniently made by stamping 50 the ends of the springs therebeneath. A clamping plate 7 is arranged to slide on the side members of the frame. A convenient

way of mounting this element 7 is by means of slots 8 in the ends thereof which receive 55 the sides of the frame. The length of said plate 7 is such that it extends a sufficient distance from the sides of the frame to enable the fingers to move it against the springs to increase the space between said 60 plate and the top of the frame. The plate 7 may be compressed until it reaches the shoulders 4. The ends of the springs are also united to the clamping plate 7, a convenient manner being through means of 65 tongues 6 stamped therefrom and beneath which the ends of the springs are clamped. The ties 9 are extended between the top 3 of the frame and the clamping plate 7 and are held securely in bundles, the individual 70 ties of which may be readily displayed by turning them over and without removing the clamping device or holder. In the case of the sale of one or more ties from a package, they are easily removed by pressing the 75 pressure plate 7 against the springs to relax the hold on the package of ties.

Having described our invention, we claim, A device for holding a bundle of neckties together, comprising a portable rectangular frame having end and side members, oppositely disposed shoulders on the side members adjacent to one end member, a clamping plate having transverse slots adjacent to its ends through which the side 80 members of the frame extend and form guides upon which said plate is slidable, said shoulders forming stops for the plate, the ends of said plate terminating adjacent to the side members, the other end member 85 forming a stationary abutment between which and said plate a bundle of neckties is insertible, and springs connected to the first named end member and to said plate and exerting pressure to hold the ties between 90 said plate and the last named end member, whereby an assortment of neckties may be held in a bundle and moved from place to place for display, substantially as specified.

In testimony whereof we affix our signatures, in presence of two witnesses.

WALTER S. RUTLEDGE.
JOHN H. DE WEESE.

Witnesses:

MELLIE GALLOWAY,
MATTHEW SIEBLER.
